US0D1063117S

(12) **United States Design Patent** (10) Patent No.: **US D1,063,117 S**
(45) Date of Patent: ** Feb. 18, 2025

(54) **SCAFFOLDING COMPONENT**

(71) Applicant: **Tobler AG**, Rheineck (CH)
(72) Inventors: **Timo Kuster**, Rheineck (CH); **Hasim Tamer**, Kreuzlingen (CH); **Ridvan Yazici**, Diepoldsau (CH)

(**) Term: **15 Years**

(21) Appl. No.: **35/518,123**

(22) Filed: **Aug. 22, 2022**

(80) **Hague Agreement Data**

Int. Filing Date: **Aug. 22, 2022**
Int. Reg. No.: **DM/223638**
Int. Reg. Date: **Aug. 22, 2022**
Int. Reg. Pub. Date: **Aug. 25, 2023**

(30) **Foreign Application Priority Data**

Mar. 1, 2022 (WO) WIPO114240

(51) **LOC (15) Cl.** **25-04**

(52) **U.S. Cl.**

USPC **D25/68; D25/124**
